United States Patent

Des. 235,185
Patented May 27, 1975

235,185

CANISTER WITH LID OR SIMILAR ARTICLE

Walter B. Achenbach, Toledo, Ohio, assignor to
Owens-Illinois, Inc., Toledo, Ohio

Filed Aug. 27, 1973, Ser. No. 391,613

Term of patent 14 years

Int. Cl. D9—02; D7—07
U.S. Cl. D7—79

FIG. 2

FIG. 3

FIG. 4

FIG. 5

FIG. 6

FIG. 7

FIG. 8

FIG. 9

FIG. 1 is an elevational view of a canister with lid or similar article embodying my new and ornamental design in the size and proportions of a coffee canister.

FIG. 2 is a top plan view thereof.

FIG. 3 is a bottom plan view thereof.

FIG. 4 is an elevational view of a canister with lid or similar article embodying my new and ornamental design in the size and proportions of a sugar canister.

FIG. 5 is a top plan view thereof.

FIG. 6 is a bottom plan view thereof.

FIG. 7 is an elevational view of a canister with lid or similar article embodying my new and ornamental design in the size and proportions of a flour canister.

FIG. 8 is a top plan view thereof.

FIG. 9 is a bottom plan view thereof.

I claim:

The ornamental design for a canister with lid or similar article, as shown and described.
